UNITED STATES PATENT OFFICE.

WILLIAM M. BUSBY, OF MATTHEWS, MISSOURI.

FIRE-ESCAPE.

1,318,262.

Specification of Letters Patent.

Patented Oct. 7, 1919.

Application filed September 15, 1916. Serial No. 120,321.

To all whom it may concern:

Be it known that I, WILLIAM M. BUSBY, a citizen of the United States, residing at Matthews, in the county of New Madrid and

5 State of Missouri, have invented certain useful Improvements in Fire-Escapes, of which the following is a specification, reference being had therein to the accompanying drawing.

10 The invention relates to fire escapes, and more particularly to the class of flexible ladders for use as fire escapes.

The primary object of the invention is the provision of a ladder structure wherein the 15 chain members carry at equal distances apart sets of rungs, each of which is of novel form so as to properly brace the ladder when in use to hold the same spaced from the wall of the building and also serving to steady said 20 ladder when suspended from the building.

Another object of the invention is the provision of a ladder of this character which may be rolled to occupy the least possible space when not in use and which may be 25 quickly extended and connected to the window frame of a building for permitting the easy escape of occupants during conflagration, such ladder being composed of chains or other flexible connections and 30 spacing members for engaging the building to hold the ladder away from the same while in use.

A further object of the invention is the provision of a ladder of this character which 35 is simple in construction, thoroughly reliable and efficient in use, strong, durable and inexpensive in manufacture.

Other objects will be in part obvious and in part hereinafter set forth.

40 The invention accordingly consists in the features of construction, combination of elements and arrangement of parts which will be exemplified in the construction hereinafter described, and the scope of the application of which will be indicated in the appended claims.

In the accompanying drawing:

Figure 1 is a front elevation of a ladder constructed in accordance with the invention 50 extended for use;

Fig. 2 is an enlarged fragmentary side elevation of the ladder showing one of the braces against the wall of the building;

Fig. 3 is a vertical sectional view through

a support for the ladder, the same being 55 rolled or in collapsed form thereon;

Fig. 4 is a top plan view of one of the ladder rungs or steps.

Similar reference characters indicate corresponding parts throughout the several 60 views of the drawing.

Referring to the drawing in detail, the numeral 5 designates generally the chain members of the ladder, although other suitable flexible connections can be substituted 65 therefor, and these chain members at intervals thereof have connected thereto metal castings or members 6 which carry the steps or rungs of the ladder, which will be hereinafter fully described. Suitably mounted 70 on the uppermost casting 6' of the ladder are hooks 8 which, when in use, are adapted to embrace the sill 9' of a window frame in a building so that the ladder may be suspended from the building and outside there- 75 of as is clearly shown in Fig. 1 of the drawing.

Each step or rung comprises a U-shaped frame 7 which is formed with terminal engaging portions 8' embracing the castings or 80 members 6, which have passed therethrough a hanger rod 9, and within this frame 7 and suitably fixed thereto is a foot supporting stirrup 10 which is of the form shown in Fig. 4 of the drawing so that when the foot 85 of the user is placed upon the step or rung the stirrup 10 will form a bearing or rest for the foot when ascending or descending the ladder in the use thereof.

The castings or members 6 which are connected to the chain members 5 of the ladder will hold the steps or rungs in a horizontal plane, and upon each frame 7 thereof, medially of the same or at the closed side thereof, are anchoring spurs or pins 11 which are 95 adapted to bite into the wall of the building when the ladder is suspended from the window frame thereof so that the ladder will be firmly held against swinging inwardly toward the wall and thereby sustain the ladder braced or supported with relation to the wall at certain points thereof, and thus in this manner the ladder will be prevented from engaging the wall between the braces and will permit free access to the steps or 105 rungs when the same is in use.

The rod 9 is passed through each pair of castings or members 6 and the limbs of the

frame 7 so that the ladder is rendered rigid and will be properly supported upon the chain members 5 of the ladder.

In Fig. 3 there is shown a ladder support 5 12 which may be of any approved form having the windlass or drum 13 on which is coiled the ladder for the holding thereof, when not in use, in compact form, the braces 10 being of a size to avoid interference with the coiling of the ladder upon the support and are so mounted as to permit swinging movement upwardly to be placed between the adjacent portions of the chains when the ladder is wound on the support.

15 The frames 7 form the braces to the ladder when extended, as said frames contact at their closed sides with the wall of the building and the anchoring pins 11 bite into the same and thereby secure the ladder in extended position from the wall for the proper 20 hanging of the same for use.

Having thus described my invention, I claim:

1. A fire escape including flexible members, a plurality of rung carrying members 25 connecting portions of said flexible members, a plurality of spacing brackets connected with the rung carrying members, rungs engaging the rung carrying members and 30 spacing brackets to hold the same together,

and a support on said brackets and extending inwardly toward said rungs to provide auxiliary foot supporting mediums.

2. A fire escape including flexible members, a plurality of rung carrying members 35 connecting equal portions of said flexible members, a plurality of U-shaped spacing brackets connected with the rung carrying members, rungs engaging the rung carrying members and spacing brackets to hold 40 the same together, and supports on said brackets extending inwardly toward the rungs and in the same plane with the said brackets to provide auxiliary foot supporting 45 mediums.

3. A fire escape including flexible members, a plurality of rung carrying members connecting portions of said flexible members, a plurality of U-shaped spacing brackets 50 connected with the rung carrying members, rungs engaging the rung carrying members and spacing brackets to hold the same together, supports on said brackets extending 55 inwardly toward the rungs and in the same plane with said brackets to provide auxiliary foot supporting mediums, and anchoring pins on said brackets for engaging a wall to hold the fire escape in position.

In testimony whereof I affix my signature.
WILLIAM M. BUSBY.
